UNITED STATES PATENT OFFICE.

CHARLES OSTEN, OF NEW HAVEN, CONNECTICUT.

DETACHABLE HEEL.

1,306,389.

Specification of Letters Patent. Patented June 10, 1919.

Application filed August 19, 1918. Serial No. 250,439.

To all whom it may concern:

Be it known that I, CHARLES OSTEN, a citizen of the United States, residing at New Haven, in the county of New Haven and 5 State of Connecticut, have invented a new and useful Improvement in Detachable Heels; and I do hereby declare the following, when taken in connection with the accompanying drawings and the characters of 10 reference marked thereon, to be a full, clear, and exact description of the same, and which said drawings constitute part of this application, and represent, in—

Figure 1 a side view of the heel portion 15 of a shoe showing my detachable heel connected therewith.

Fig. 2 a front view of the same.

Fig. 3 an underside view of the heel portion with the top lift removed.

20 Fig. 4 a longitudinal sectional view of the same.

Fig. 5 a top view of a top lift with the top lift plate attached thereto.

25 Fig. 6 a longitudinal sectional view of the same.

Fig. 7 a sectional view through the heel with the top lift secured in place.

Fig. 8 a plan view of a heel provided with a top lift of ice creeper type.

30 Fig. 9 a sectional view on the line 9—9 of Fig. 8.

Fig. 10 a perspective view of the locking key detached.

This invention relates to an improvement 35 in detachable heels, and particularly to means for securing the top lift in place, and is adapted for use in connection with top plates formed from rubber, leather, metal or any other material, the object of the invention being a simple arrangement of parts 40 whereby top lifts may be readily secured to heels of boots and shoes and removed therefrom as occasion may require; and the invention consists in the construction herein- 45 after described and particularly recited in the claim.

In carrying out my invention I form the 50 regular heel 11 with a recess 12 in its under face, and in this recess I secure a heel plate 13 preferably struck up from sheet metal and formed with a series of transverse straps 14, 15 and 16 of different lengths and tapered at their ends, the wider strap being near the forward end. These straps may be struck 55 out from the heel plate so as to be integral therewith, or may be formed separately and

attached to the plate. The plate is also formed at its forward edge with a downwardly projecting flange 17 the central portion 18 of which is cut away in line with the 60 strap 16 for the purpose as will hereinafter appear. The flange is longer than the width of the strap, and the ends 19 and 20 are turned inward. Preferably and as herein shown the inner end of the plate will be 65 formed with a slight depression 21 for the purpose as hereinafter specified. In connection with a heel thus provided with a heel plate, I employ a top lift 22 which may be formed from rubber, leather, wood or any 70 other material. Secured to the upper face of the top lift 22 is a top lift plate 23 corresponding in dimensions to the heel plate 13 and is formed with transverse straps 24 and 25 respectively located so as to pass between 75 the straps 14 and 15 and the straps 15 and 16. These straps are of different lengths and tapered at their ends so that the straps on the two parts form a continuous taper. The top lift with its plate attached is placed 80 against the heel, and a key 26 inserted between the two plates so as to pass between the several straps thereon. This key is tapered corresponding to the taper of the straps so as to firmly connect them together. 85 This key is formed at its inner end with a slight recess 27 to engage with the projection 21 on the heel plate before referred to. It is also formed near its outer end with a slight projection 28 which will engage with the 90 edge of the flange 17 so that the key is locked in position. The key is also formed with a downwardly projecting lip 29 which closes the openings between the edge of the heel and the top lift and forms a finger-piece by 95 which the key may be pried out as occasion may require. Instead of forming the top lift from rubber, leather or similar material it may be formed from a sheet of metal 30, as shown in Fig. 9 of the drawings, in which 100 case the plate will be slightly larger than the opening 12 in the heel so as to rest upon the edge of the heel, and this plate will be formed with downwardly projecting prongs 31 more or less in number, which serve for 105 use on icy walks. This metal plate may be readily removed when not required for use, and replaced by another top lift. This construction permits the use of a top lift of ordinary construction; that is, for instance, 110 a rubber heel having a flat upper face as it is only necessary to attach the top lift plate to

it to enable it to be connected with a heel, and so that after the heel is once prepared and provided with a heel plate, various top lifts may be used by securing the top lift plates in place. By using a tapered key the parts are not only firmly held in position, but when occasion requires the key is more readily removed than might be the case with a straight key if such a straight key should 10 become rusty so as to adhere to the straps. By forming the straps as an integral part of the plates they have a certain amount of spring action so as to increase the cushioned effect of the heel.

15 I claim:—

Means for attaching detachable heels comprising a heel plate formed with a series of downwardly extending straps of different lengths and tapered at their outer ends, said 20 plate also formed at its forward edge with a

downwardly projecting flange, the central portion of which is partially cut away, a top lift plate formed in its upper face with a series of straps of different lengths and tapered at their ends and adapted to enter 25 between the straps on the heel plate, and a tapered key corresponding in width to the distance between the inner walls of the ends of the straps between which it is entered, said key formed with a downwardly projecting lip, and with a projection near its outer end to engage with the inner edge of the central portion of the flange on the heel plate.

30 In testimony whereof, I have signed this specification in the presence of two subscribing witnesses.

CHARLES OSTEN.
